UNITED STATES PATENT OFFICE.

ABRAHAM B. LANDIS, OF ENFIELD, PENNSYLVANIA.

CUTTER-HEAD.

1,221,193.

Specification of Letters Patent.

Patented Apr. 3, 1917.

Application filed March 4, 1912, Serial No. 681,413. Renewed February 24, 1917. Serial No. 150,845.

To all whom it may concern:

Be it known that I, ABRAHAM B. LANDIS, a citizen of the United States, residing at Enfield, Montgomery county, and State of Pennsylvania, have invented and discovered certain new and useful Improvements in Cutter-Heads, of which the following is a specification.

My said invention consists in certain improvements in the details of construction and arrangement of parts of cutter-heads for cutting threads on bolts, screws, etc., whereby a structure is provided which is compact and rigid and adapted to do work of a fine and accurate character, as will be herein-after more fully described and claimed.

Referring to the accompanying drawings, which are made a part hereof and on which similar reference characters indicate similar parts,

Figure 1 is a front elevation of a cutter-head constructed in accordance with my said invention,

Fig. 2 a central section through the same on the dotted line 2—2 in Fig. 1,

Fig. 3 a detail section on the dotted line 3—3 in Fig. 2,

Fig. 4 a detail view illustrating in elevation a feature of construction shown in section in Fig. 3,

Fig. 5 a face view of the body of the cutter-head stripped of the other mechanism.

Fig. 6 a view of the cutter and cutter-holder showing the cutter in face elevation,

Fig. 7 an edge view of the same,

Fig. 8 an end view as seen when looking in the direction indicated by the arrows on the dotted line 8—8 in Fig. 7, and

Fig. 9 a separate view of a coiled spring forming a feature of the construction.

In said drawings the portions marked A represent the body of the cutter-head, B a sleeve for mounting the same on the turret of the machine and C the cutter-holder.

The body or base A comprises a casting having a central hollow shank and formed with intersecting T-grooves α in its face. Said grooves run at right angles with each other, equi-distant from the central aperture, and on lines tangential to a circle the axis of which is the axis of the head. One end of each groove runs to the outside of the head and the other end cuts into the groove which extends at right angles therewith on the opposite side of the head. A ring A¹ is mounted on the front edge of the body by means

of a screw-threaded connection, said ring covering the outer open ends of each of said slots. The central hollow shank of said body is circular in form and extends rearwardly within the sleeve B to which it is connected by means of a key b . Said key secures said parts to rotate together but permits an independent longitudinal movement.

A spring 10 is mounted in a perforation formed partly in the sleeve B and partly in the adjacent part of body A and is interposed between a radial pin 11 carried in said body A and a pin 12 carried in the sleeve B. The tension of said spring acts to normally hold body A rearward against the end of sleeve B but permits the independent longitudinal movement when required.

A ring A² is also mounted upon body A, its forward edge bearing against the rear face of ring A¹ and its rear end surrounding a disk A³ to which it is connected by means of a tangential screw 14, mounted to revolve in bearings in said ring, the threads of which engage with a thread in the periphery of said disk. A collar 15, is clamped around the outer end of screw 14 by means of a handle 16, having a tapered screw-threaded inner end which

screws into a perforation in ring A² adjacent to said collar and impinges against one side thereof to lock it from rotation. Another collar 17 is secured by a pin 18 to the outer end of said screw and turns therewith. The adjacent ends of said collars 15 and 17 are provided with lugs 19 and 20, respectively, adapted to strike when said screw is turned, for a purpose to be presently described.

A heavy torsional spring 21 is mounted between disk A³ and body A, the opposite ends of which are bent at right angles, and reversely, point 22 engaging with a perforation in said disk A³ and the point 23 at the opposite end engaging with a perforation in said body A. The tension of said spring is directed to turn the disk A³ and ring A² connected therewith to open the die, as will be presently described.

A locking pin 24 is mounted in collar B and is adapted to engage with a perforation 25 in disk A³, when said perforation is brought to register therewith.

The inner end of ring A² is formed with a series of cam faces 26 on its interior, as best shown in Fig. 1, said cams being in transverse position in line with the grooves α in the body A.

The cutter-holders C are formed with sliding heads C¹ offset from the main body and connected therewith by neck-pieces c. Said heads are adapted to be mounted and slide in the groove a in the body A, carrying the holder C and the cutter, or chaser, mounted thereon a sufficient distance from the face of the body for the purposes of the device. The neck pieces c project through the narrow part of grooves a connecting the holders proper with the sliding heads and forming a unitary structure. Each sliding head C¹ has a projecting arm c² which lies in the bottom of its groove projecting across the groove on the opposite side at right angles thereto and under the head in said other groove. By this means a long rest and bearing is provided for each head so that said heads may be slid in and out in relation to the axis of the head to adjust the die for work of different sizes without weakening the supports or impairing their rigidity. Each of said sliding heads C¹ is formed with a perforation c³ in which is mounted a coiled spring 27, the outer end of which projects and bears against the adjacent side of the head C¹ in the groove extending at right angles with the groove containing the head carrying the spring. Said springs thus tend to slide the several heads outwardly and hold the die normally open. Each one of the several cam faces 26 bears upon a curved face 28 on the end of the appropriate head C¹, opposite the perforation c³ containing the spring so that the turning of ring A² carrying said cam faces in one direction operates to slide said cutter-holders inwardly to close the die, while the turning of said ring in the opposite direction permits the springs 27 to expand and slide said heads outwardly and open said die.

Each cutter-holder carries a chaser, or cutter, 30 mounted in a suitable recess in the face thereof. Said chaser is adapted to be adjusted by a screw 31 mounted in the holder and engaging a screw thread in the back of said chaser. Each chaser is formed with a dove-tail shaped shoulder engaging under a correspondingly formed flange 32 in the face of said holder C and its opposite edge 33 is likewise formed and is engaged by a correspondingly tapered sliding clamp 34. Said clamp is operated by a screw 35, mounted in a screw-threaded perforation in holder C and formed with a conical point which engages with a conical socket in the adjacent side of said clamp. A spring 36 operates said sliding clamp 34 reversely to the action of the screw 35 so that when screw 35 is backed to release said clamp, spring 36 will automatically slide said clamp outwardly and release the cutter.

In operation, the parts being in closed position as shown in Fig. 1, the point of

each cutter stands in a radial line with the axis of the cutter-head and the cutting is done by feeding the work thereto. When the cutting has proceeded to the point desired, the body A is drawn outward in sleeve B by the action of the cutters, as is well understood, until pin 24 is free from its engagement with plate A³. As soon as these parts are released spring 21 expands turning ring A² to bring the low portion 75 of the cam faces 26 opposite the high points of the bearing faces 28 permitting springs 27 to expand and open the die, releasing the work. When it is desired to close the die, the operator turns ring A² through the medium of handle 16 which winds up spring 21 and as soon as perforation 23 registers with the end of locking pin 24, spring 10 expands throwing said locking pin into said socket and the face of disk A³ against the 85 end of sleeve B, when the die is closed and the operation may be repeated.

When it is desired to adjust the die for different sizes of work it may be done by turning screw 14 to carry the ring A² to a 90 different position in relation to the disk A³ thus shifting the normal position of the cams 26 and providing for a die of a different size.

In operation it is frequently desired to 95 make first a rough cut and then a finishing cut on the same work. In such cases the first cut is made and then screw 14 is turned to throw shoulder 20 around into contact with the opposite side of shoulder 19 which will adjust ring A² to contract the die sufficiently for the finishing cut. By this means a finishing cut of accurate and standard adjustment may be secured in all 100 work of the character requiring such finishing cut. 105

Having thus fully described my said invention, what I claim as new and desire to secure by Letters Patent, is:

1. A cutter-head comprising a body 110 formed with grooves in its face extending at right angles to each other and intersecting, cutter-holders formed with heads adapted to be mounted and slide in said grooves, springs interposed between the 115 head in one groove and the head in another groove at right angles therewith, a ring surrounding said head provided with a series of cams adapted to bear against the sliding heads opposite to said springs, means for turning said ring to close the die, and means for locking the parts with said die in closed position, substantially as set forth.

2. A cutter-head comprising a body 125 formed with ways in its face extending tangentially and at right angles to each other, those extending in one direction intersecting and crossing those extending in the other direction, cutter-holders mounted to 130

slide in said ways, means in said ways for normally holding said cutter-holders outwardly, means in operable relation with each of said cutter-holders adapted to operate them inwardly, and means for locking said parts in closed position, substantially as set forth.

3. A cutter-head comprising a body formed with intersecting ways in its face extending at right angles and tangentially to a circle the center of which is the axis of said head, cutter-holders mounted to slide

in said ways, means interposed between said holders for normally sliding said holders outward, and means for forcibly sliding 15 them inward, substantially as set forth.

In witness whereof, I have hereunto set my hand and seal at Washington, District of Columbia, this 16th day of February, A. D. nineteen hundred and twelve.

ABRAHAM B. LANDIS. [L.S.]
